FIG. I.

Fig. 4. 19 Fig. 5. 20 29

FIG. G.2.

Technical drawing of a mechanical assembly, likely a pump or valve mechanism, showing various components labeled with numbers 5 through 40. The drawing includes a base plate with a central bearing housing, a vertical rod assembly with a handle, and a horizontal pipe assembly with a valve. A handwritten label "FIG. G.2." is present on the left side of the drawing.

ATTORNEY

UNITED STATES PATENT OFFICE.

LENTHEL STANTON, OF SPOKANE, WASHINGTON.

SPRINKLER.

Application filed August 10, 1925. Serial No. 49,294.

This invention relates to improvements in sprinklers of the rotary type, the rotary actuation being effected by means shown in my application filed January 20, 1925, Serial No. 3,623, for improvement in sprinklers.

The object of this invention is to provide novel means for deflecting or controlling the sprinkling stream whereby the spread of the latter may be confined within a square area or one bordered by straight lines.

A further object of the invention, irrespective of the size or shape of the area, is to distribute the water from a single stream in such a manner that all of the area sprinkled will be uniformly irrigated throughout the radial sweep of the stream.

A further object is to provide means whereby the rotary movement of the nozzle may be arrested and held in such arrested position when it is desired to sprinkle a given area for a prolonged period of time.

Other features and objects of my invention will be more fully described in connection with the accompanying drawings and will be more particularly pointed out in and by the appended claims.

In the drawings:—

Fig. 1, is a plan view of the most improved form of my invention.

Fig. 2, is a view in side elevation thereof.

Fig. 3, is a view looking from the right of Fig. 2.

Fig. 4, is a bottom face view of the stream deflecting face of my improved stream deflecting lever.

Fig. 5 is a view in side elevation thereof.

Fig. 6, is a diagrammatic view in plan, showing how the device irrigates a square area.

Fig. 7, is a view in side elevation of the stream as it issues from the nozzle.

Fig. 8, is a cross sectional view of the stream on line 8—8 of Fig. 6.

Like characters of reference designate similar parts throughout the different figures of the drawings.

As shown, my invention includes a hollow base 1 having a cap 2, suitably secured to said base as by means of screws 3. The base has a tangentially disposed intake 4, adapted to be connected with a garden hose, and the water whirling in said base 1, advances a ball 5, against the downturned end

6, of an arm 7. Arm 7, is secured to a hollow sleeve 8, journalled in hub 9, on which latter, a nozzle 10 rotates. A nozzle portion 11, directs a single sprinkling stream at an angle to the vertical, as shown in Fig. 2, and the same has a passage 12, which communicates with sleeve 8, so that in any position of the nozzle, the latter will be in full registry with said sleeve.

The foregoing, constituting the actuating means for rotating the nozzle, is similar to that shown in my above identified application and I have generally referred to it in this case in order to show a completely operative structure.

The top of nozzle 10, above nozzle portion 11, is recessed at 13 thereby providing pivot lips 14, between which means, preferably in the form of a lever 15, is disposed. A substantially horizontal pivot pin 16, extends through said lips and lever and permits the latter to be rocked as the nozzle 10 rotates, or permits of rocking adjustment of said lever into fixed stream deflecting positions, as will presently appear.

Said lever 15, has a deflecting end 17, projecting from one side of pivot 16 and disposed above and preferably beyond the terminal 18, of said nozzle portion 11. The outer stream deflecting face 19, of said deflecting end 17, is substantially and preferably flat and the margin 20 is semi-circular, as shown in Fig. 4. This form of face, when advanced into contact with the stream issuing from end 18, not only flattens the longitudinal arch of the stream, but also spreads the latter, and in addition, transversely arches the same, as will be later described. Immediately in the rear of the outer flat face 19, the deflecting end is provided with laterally notched portions which are preferably in the form of a recess 21 extending throughout the width of the deflecting end 17, the base portion 22, of said recess, being inclined to the normal plane of face 19, and merging into a shoulder 23, of said lever 15. A preferably resilient plate 24, proportioned to have an edge flush fit with said recessed portion, is anchored thereto at 25. An adjustment, in the form of a screw 26, threaded in said deflecting end 17, provides means for flexing said plate 24 to the right of Fig. 5, to variously decrease the effective depth of the recessed portion 21, with which the stream engages. In Fig. 5, the plate 24,

lies in flat abutting relation with the base 22, of said recess, so that shoulder 21, opening through the lateral edges of end 19, forms laterally disposed notched portions 5 which serve to divert portions of the main stream into lateral streams. In cases where such lateral streams are not desired, the plate 24 may be adjusted to the right of Fig. 5, sufficiently so that the stream will end 10 gage a smooth flat surface, when the end 27, of plate 24, is flush with the edge 28, of shoulder 21. It will be noted that face 19, is inclined so that the outer portion 29, will extend downwardly toward 15 the stream.

The actuating end 30, of lever 15, extends on the opposite side of pivot 16 in overhanging relation to the base 1, and the same is preferably provided with an extension 31, 20 forming stock for an adjustment screw 32. A cam follower or rod 33, extends through the actuating end 30, and may be provided with a cranked end 34, to facilitate swivelled adjustment of said rod. The screw 32, 25 serves to hold said rod in its adjusted position. The lower end 35, depends downwardly into the path of a cam, which I will next describe.

I have shown a cam fixed or cast integral- 30 ly on the lid 2, of base 1, the cam being substantially concentrically disposed about the nozzle 10, or rather about the axis of rotation of said nozzle. Said cam includes hill portions 36 and vale portions 37 symmetri- 35 cally disposed and arranged to provide for control of the sprinkling stream so that the latter will be confined to an area bounded by straight lines. In the present construction, the cam is designed to control the 40 stream so that a square area will be sprinkled. The lower end of rod 33, traverses the periphery of the cam and when riding against the hill portions 36, the deflection end 17 is depressed to flatten the stream to 45 a relatively extreme extent whereas when the rod enters the vales 37, the lever 15 is rocked by the stream and releases the latter for a further projection so that the 50 stream will reach corner portions of the area. It will be noted that the major portions of the hills 36, are concentric with nozzle 10. Now with different pressures, and different extents of areas to be sprinkled, I provide a compensating adjustment to cor- 55 respondingly vary the rocking movement of lever 15. Thus, it will be seen from Fig. 3, that rod 33, is offset at 38, so that by ro- 60 tative adjustment of said rod 33, the extent of rocking movement of lever 15, can be changed.

In some cases, it may not be desired to 65 sprinkle a square area although it is desired to take full advantage of the functions of deflection, in which case, I provide the fol- lowing means.

The rod 33, may be either removed or adjusted upwardly out of range of the cam so that it will not be actuated thereby. A screw 39, threaded through lever 15, at the right of pivot 16, viewing Fig. 2, impinges 70 on the base 40, so as to hold lever 15 in the desired stream deflecting adjustment so that the nozzle 10 will revolve and sprinkle a circular area, the stream having the same spread and projection at all times. Of course, when the cam rod is active, screw 39, 75 will be adjusted high enough not to contact with base 40 and thereby interfere with actuation of the lever 15 by the cam.

I will next describe the novel means for 80 localizing the stream on a single area thereby converting the rotary sprinkler into a stationary sprinkler.

The cam has interior cavities 41, there being shown, four in all. The nozzle 10 is 85 provided with a lug 42 which carries a stop rod 43, the latter being loosely hooked through the lug 42, as clearly shown. Rotation of the nozzle is always in the direction of the arrow shown in Fig. 1, when the present form of water actuating means is employed. Ordinarily when the device is rotating, the rod 43, hangs loosely outside the cam, as shown in Fig. 2. However, 90 should it be desired to hold the nozzle in a fixed position, the lower end of rod 43 would be inserted into one of the cavities 41, as shown in Fig. 1, and this adjustment would prevent rotation of the nozzle, the ball 5, idly traversing the hollow base 1. 100

In Fig. 6, I have diagrammatically shown a square area 45, with the main stream 46 projecting to one of the shorter radial limits of the area. This plan view shows the spread of the main stream, as a result of deflection, and in Fig. 8, I have indicated the manner in which the stream is arched. It will be noted that the vales 37, line up with the corners 47, of the area. Now as the stream 46 approaches a corner, the rod 33 will gradually recede into a vale 37, thereby permitting lever 15 to be rocked by the stream so as to release the latter to a higher arch and a greater extent of projection. However, this releasing action is not 115 sufficient to eliminate flattening the stream's arch, entirely but only to very slightly release the same.

In Fig. 7, I have diagrammatically shown the main stream in side elevation, the spread of drop from the outermost to the innermost limits being indicated 48 and 49, respectively, due to deflection of the stream by lever 15. Now it will be clear that such a spread of water would leave the radially innermost area from 49 to 50, comparatively dry, except for the falling mist. Hence, the lateral streams 51, make up this deficiency and thoroughly irrigate the radially innermost area not only because they run 125 130

constantly, but also because they rotate at a much less rate of speed by reason of their nearer proximity to the sprinkler. Thus, the major portion of water is deposited between 49 and 48, but for short periods of time, whereas, the streams 51, are constantly traversing the same area. The foregoing has been worked out, most successfully in actual practice.

10 It may be stated that the ball 5, causes an intermittent rotation of the nozzle, the same as in my prior case.

It will be noted that I do not employ any springs in connection with holding or rocking lever 15, the latter being reacted upon by the water, to render the cam and adjusting means 39, effective.

15 It is believed that my invention will be fully understood from the foregoing description, and while I have herein shown and described one form of my invention, I do not wish to be limited thereto except for such limitations as the claims may import.

I claim:—

20 1. In a sprinkler, a base having a nozzle revoluble about a substantially vertical axis and having a nozzle portion inclined to the vertical, a stream deflecting lever pivotally mounted on the top of said nozzle above said nozzle portion to rock about a substantially horizontal axis and revolve with said nozzle, said lever having a stream deflecting end overhanging said nozzle portion on one side of the pivotal mounting of said lever, and said lever having an actuating end overhanging said base on another side of said pivotal mounting of said lever; a follower rod having its upper end fixed to the actuating end of said lever and said rod depending substantially vertically therefrom, and a cam on said base having hills and vales in the path of the lower end of said follower rod to rock said lever and alter the char-

acter of stream discharged by said nozzle portion as said nozzle revolves. 45

2. In a sprinkling device for sprinkling a square area, a base, a sprinkling nozzle rotatable on said base, stream deflecting means on said nozzle and rotatable therewith, a cam on said base and having hills 50 and vales, and means on said deflecting means cooperating with said cam for actuating said deflecting means to serially release and restrict the stream in a predetermined manner to a square area when said base is located with respect to said area to dispose the hills and vales of said cam in determined relation to said area.

3. In a sprinkler, a base, a nozzle rotatable on said base for directing a main stream, a stream deflecting lever mounted on said nozzle and having a main stream deflecting end for flattening the arch of the stream to distribute the water of the main stream over substantially all of the outer 65 radial half being sprinkled, and said deflecting end having a stream deflecting notch directing streams of water from the axis of the main stream laterally of the latter and covering substantially the inner radial half 70 of the area being sprinkled.

4. In a sprinkler, a base, a nozzle rotatable on said base for directing a main sprinkling stream, a stream deflector having a relatively enlarged deflecting face having 75 a rounded edge for spreading the main stream, said face having a transversely disposed groove opening at the edges of said face for deflecting lateral streams from the main stream, and means for varying the action of said groove or rendering said groove ineffective.

In testimony that I claim the foregoing as my own, I hereby affix my signature.

LENTHEL STANTON.
